UNITED STATES PATENT OFFICE.

FRED HAMDEN COLE, OF YUMA, COLORADO.

STORE-COUNTER.

1,348,087.

Specification of Letters Patent. Patented July 27, 1920.

Application filed October 6, 1919. Serial No. 328,776.

To all whom it may concern:

Be it known that I, FRED HAMDEN COLE, a citizen of the United States, and a resident of Yuma, in the county of Yuma and State 5 of Colorado, have invented certain new and useful Improvements in Store-Counters, of which the following is a specification.

My invention is an improvement in store counters, and has for its object to provide a 10 device of the character specified, especially adapted for use in grocery stores, for making up orders, wherein the counter has a series of compartments, each provided with a sliding cover arranged to be slid to one end 15 of the compartment, and to be stood at the said end in vertical position, each of the said covers bearing the name of the customer whose order is to be filled.

Another and more specific object is the 20 provision of a counter of this character in which the compartment covers are provided with means whereby they will be prevented from being slid off the counter.

In the drawings:—

25 Figure 1 is a perspective view of the improved counter looking from the rear, and with the compartments open,

Fig. 2 is a transverse vertical section,

30 Fig. 3 is a perspective view of the counter from the front, with the compartments closed,

Fig. 4 is a longitudinal section.

In the present embodiment of the invention, a suitable casing is provided consisting in the present instance of a front wall 1, a rear wall 2, and walls 3, and a bottom 4. The casing is divided into a series of similar compartments by partitions 5 extending transversely of the casing, and a cover 6 is 35 provided for each compartment.

40 It will be seen referring to Fig. 1, that the tops of the partitions 5 are flush with the upper edges of the sides and ends, and cleats 7 are secured to the partitions 5 at their tops. A finishing strip 8 is secured to the top of each partition, and a somewhat similar strip 8^a is secured to the top of each 45 end, and these strips extend beyond the partitions slightly as shown in Fig. 4, but not 50 far enough to extend beyond the outer faces of the cleats.

Each of the covers 6 rests upon the cleats when in closed position, and the said covers are of the same thickness as the finishing 55 strips, so that their upper surfaces will be

flush with the upper faces of the finishing strips when the covers are in place.

Referring to Fig. 2, it will be seen that the cleats do not extend to the front wall 1, but are spaced apart from the said wall and 60 are rounded at their upper front corners as indicated at 9, the arrangement being such that when the covers are pushing forwardly they may be dropped down into the compartments in the manner shown in Figs. 1 65 and 2. Each cover has on its underface transverse cleats 10 and 10^a for strengthening the same, and at its rear end a handle 11 for convenience in handling the cover.

The cleats A not only strengthen the 70 cover but are adapted to engage against the casing when the covers are in closed position for preventing the covers from being slid off the casing.

A legend may be placed on the rearmost 75 cleat 10 if desired, and this cleat is so arranged that when the cover is opened, the legend will be well above the top of the casing and clearly visible.

In use, the casing may be arranged upon 80 the counter as indicated at 12, or it may be arranged in any other suitable manner, and it will be noticed referring especially to Fig. 2 that the plate 4 forming the bottom 85 of the compartments is spaced well above the floor, and that the rearmost wall is removed below the said bottom, to provide ventilation and to permit the casing to be kept clean. The front and ends are suitably ornamented as for instance by panels. 90

The device is especially adapted for country stores, as it does not take up extra floor space, and can be used as an ordinary counter either in retail or wholesale stores. Any 95 one clerk can fill the order and any other clerk can check the order out to the customer, as the order book is filed in the compartment with the goods until the articles are checked out. The front of the counter may be paneled if desired, as shown in 100 Fig. 3.

I claim—

A store counter comprising a casing divided by transverse vertical partitions into a plurality of similar compartments, cleats 105 secured in each compartment at the opposite sides thereof, near the top, and forming guides, a rigid cover slidable on the cleats in each compartment and provided with a handle, the cleats being cut away at one 110

side of the casing and rounded to permit the cover to tilt downwardly into the compartments and to assume an upright position, the rounded ends of the cleats serving 5 to retain the cover in vertical position, with the handled end thereof projecting above the top of the casing, and cleats secured

upon the under side of each cover and engaging against the inner surface of the casing when the cover is in closed position, 10 whereby to prevent the cover from being slid off the casing.

FRED HAMDEN COLE.
